Specification of Letters Patent.

Patented Jan. 16, 1917.

Application filed December 2, 1910. Serial No. 595,212.

To all whom it may concern:

Be it known that I, PAUL F. W. C. KRIPPENDORF, a citizen of the United States, residing at Lynn, county of Essex, and State of Massachusetts, have invented an Improvement in Calculating Apparatus, of which the following description, in connection with the accompanying drawing, is a specification, like characters on the drawing representing like parts.

This invention relates to calculating apparatus, and its object is to provide such an apparatus by means of which the area of material required to cut therefrom a number of shapes of various sizes may be readily and accurately determined.

The present invention, in one of its aspects, is an improvement upon the invention disclosed in Patent No. 1,166,528, granted to me Jan. 4, 1916. The general principles of the present invention are the same as those explained in the said patent. The present invention provides a calculating apparatus of this type in which the operative mechanisms have been improved and simplified so as to insure great accuracy under the most severe conditions of use.

The invention also involves provisions in the apparatus by means of which a plurality of calculations may be made simultaneously, thus enabling the area of leathers or materials required to cut different parts of the same shoe, for example, to be calculated simultaneously.

The invention also comprises means for securing an additional adjustment whereby the reading of the calculator may be varied to cover an additional factor, such, for example, as a change in the quality of leather being used.

The foregoing and other features of the invention will more fully appear from the accompanying description and drawings and will be particularly set forth in the claims.

The drawings represent a machine embodying the invention comprising means for making two calculations simultaneously, certain parts of the apparatus not being shown in detail in view of their full disclosure in my aforesaid patent.

Figure 1 is a top plan view of the entire apparatus; Fig. 2 is a top plan view of the left hand section of the apparatus with the casing and other parts removed to show the mechanism; Fig. 3 is a bottom plan view of

the chief portion of the mechanism shown in Fig. 2; Fig. 4 is a side elevation, partially in cross section, of the mechanism shown in Fig. 2; Fig. 5 is a detail in vertical cross section of the carriage for the wheel driven by the actuator; Fig. 6 is a side elevation, partially in cross section, through the carriage and showing the superimposed indicators. Fig. 7 is a view in elevation of the uppermost indicator disks.

The apparatus comprises a series of indicators similar to those shown in my aforesaid patent, these indicators being so constructed that they represent in their operative effect a series of ratios such as those existing between various lengths or sizes of shoes which, as explained in my aforesaid patent, are proportional to the areas of the shoe parts having the said lengths and being all of the same width. These indicators are shown as circular disks superimposed, the top disk being indicated at 2, and the bottom disk at 3. These indicators are located upon a common central axis, shown as a post 4 carrying at its upper end fixed thereto a disk 1, and are mounted for rotary or angular movement on the said post. The units of angular movement of the several disks are so indicated or determined as to have the aforesaid ratios to one another, and in the form shown in the drawings the diameters or circumferences of the disks vary according to the given ratios. The several indicators are provided with the equal peripheral graduations marked by the studs 5, three of which are illustrated in Fig. 1, and locking levers 6, one of which is illustrated in Fig. 1, are provided for locking the disks together in the manner described in my aforesaid patent, the uppermost indicator 2 being locked to the fixed disk 1 by a lever carried by the fixed disk, and the succeeding lower indicators being locked to the one below by similar levers.

The lowermost indicator 3 is made fast to a base 7 presenting a flat bottom surface 8, herein termed the actuator, and is provided with arms 9 supporting a hand wheel 10. It will thus be seen that when the indicators are arranged with the locking levers set at the zero points, if any lever be depressed and the indicator thereby unlocked be moved around to the left, all the indicators below or following it will move at the same time and to the same extent, so

that the movements of the actuator 7 resulting from successive movements of the indicators are always cumulative. It will also be seen that when the indicators, or 5 any of them, have been displaced to the left from the position shown in Fig. 1, they may all be returned to the zero position by grasping the hand wheel 10 and turning it in the reverse direction, as in my aforesaid 10 patent. The total angular movement of the actuator as determined by the indicators is measured by the wheel 11 which, as in my aforesaid patent, is rotated by frictional contact with said actuator and is carried 15 by a shaft 12. The desired calculations are effected, as explained in my aforesaid patent, by adjusting or moving the wheel 11 radially of the actuator 8 so as to cause it to be rotated a greater or less distance 20 as required by the same angular movement of the actuator.

In the present invention the wheel 11 and its shaft 12 are supported in a carriage 13 guided by ways 14. The framework of 25 the carriage at its ends 15 and 16 extends down between the ways, and a cross pin 17 at the end 16 extends beneath the over-hanging projection of the ways. A U-shaped lever 18 is fulcrumed at 19 to 30 the frame of the carriage and has its lower end 20 in line with the ways 14. This lever 18 is normally elevated by grasshopper springs 21 engaging it and the frame of the carriage, and a suitable handle 22 projects from the lever. The construction is such that the spring 21, normally acting to raise the U-shaped lever 18 and bringing the ends of the lever 20 against the top of the ways 14, throws the carriage upwardly at its end 15 and about the pin 17 to bring the wheel 11 into frictional contact with the surface 8 of the actuator 7. When it is desired to shift the carriage the U-shaped lever 18 is depressed by grasping 45 the handle 22, thus raising the end 20 of the lever and lowering the carriage and bringing the wheel 11 out of contact with the actuator. The carriage may then be moved freely back and forth upon the ways 50 14, and the lever 18 may be locked in its depressed position by means of the sliding pin 29 and the coöperating recess 290.

The shaft 12 carries at the end opposite from the wheel 11 a suitable registering 55 device comprising a cyclometer 23 operated from the shaft and indicating in square feet on a reading dial 24 the area of the leather. The shaft 12 also carries a wedge-shaped cam 25 rotatably adjustable thereon 60 and set so that its sides incline at equal angles to the vertical when the reading dial is at zero. The U-shaped lever 18 is provided with adjustable pins 26 having their points equidistant from the vertical plane 65 of the shaft 12. Upon the depression of

the lever 18 these points 26 coming into contact with the inclined sides of the wedge-shaped cam 25 insure the positioning of the shaft 12 to cause the dial of cyclometer to indicate zero. The object of 70 this feature of the apparatus is to insure that in operating the calculating apparatus the readings shall always start at zero. If for any reason there should be any lost motion or failure to carry the indicators 75 all back to their exact zero point there would be a slight movement away from the zero of the dial 24, but as the carriage 13 can only be moved by depression of the lever 18 the depression of this lever is made 80 at the same time to insure the setting of the dial at zero.

It is essential that the movement of the carriage 13, carrying wheel 11, radially of the actuator 8 shall be steady, subject to 85 no lost motion and capable of the finest degree of adjustment. To secure these ends I have devised the mechanism shown in the drawings. This mechanism comprises a graduated wheel 30 mounted to turn on a 90 fixed axis constituted by a stud 31 and connected by metal bands to the carriage 13, so that any movement of rotation imparted to the wheel 30 causes directly and positively a longitudinal movement of the carriage 13 upon its ways. 95

As shown, a bracket 32 is rigidly secured by screws 33 to the frame work or base of the apparatus and the curved bracket 34 is similarly secured by means of screws 35, 100 it being understood that the ways 14 are fixed upon the base or frame of the apparatus, so that these ways 14 and the brackets 32 and 34 occupy fixed positions with respect to each other. The brackets 32 and 34 are also rigidly connected by a radially disposed brace member 320 carrying the stud 31 which is held therein by a set screw 321, and locked to the bracket 34 by screws 322. See Fig. 3. The stud 31 projects upwardly through the bracket 32 and upon this stud the graduated wheel 30 is mounted to rotate. The wheel 30 is skeletonized as shown in the drawings, and carries rigid therewith a segment 37. The carriage 13 has connected therewith by a pivot 27 above the pin 17 a bar 28 sliding upon the way 14 and, consequently, moving longitudinally with the carriage but not partaking of the vertical movement of the carriage about the pin 17. This bar 28 is of substantially the same length as the segment 37. A metal band 38, preferably in one continuous piece as shown, is attached at one end 39 to the bar 28, passes thence along the segment 37, along the bar 40 pivoted at 41 to the wheel 30, thence around the hub of the wheel along the second bar 42, pivoted at 41, thence along the segment 37 beneath the end 39 to the opposite end of the bar 28 where it 115 120 125 130

is made fast at 43. A set screw 44 carried by a projection 45 bears against the center of the band and secures it to the hub of the wheel, while other set screws 46 carried by 5 the projections 47 bear against the pivoted arms 40 and 42, thus enabling a very delicate adjustment of the longitudinal position of the carriage 13 with respect to the wheel 30 to be made.

10 The wheel 30 is provided on its upper face and near its periphery with a series of 70 graduations shown in that part of the apparatus now being described as running from 1 to 22 and indicating when the machine 15 is to be used for calculating the area of shoe parts in square feet, the decimal point not being indicated. The graduations therefore run from .1 to 2.2 square feet and these graduations appear through an 20 opening in the base of the machine, as shown in Fig. 1. It is usually necessary to indicate fractional portions of the unit indicated by said graduations on the wheel 30 and to secure this indication in an accurate 25 and distinct manner I have provided a fractional scale plate 50 graduated decimal and so arranged that when it is moved to bring a given decimal thereon into line with the graduations of the graduated 30 wheel 30, the wheel 30 will be given a corresponding fractional rotation. As shown, the scale plate 50 is pivotally mounted at 51 on the radial plate 60. This radial plate 60 is mounted to pivot or swing about 35 the stud 31 and it carries at its forward edge a scale 61 which, in the case of an apparatus such as that illustrated for use in connection with shoe parts, bears the designations of the different shoe widths and, 40 as shown, running from AA to EE. The fractional scale plate 50 is connected to a segmental plate 52 by a metal band 53 attached at its ends to the segmental plate 45 and passing around the hub 54 of the plate 50. The segmental plate 52 rests and slides upon the radial plate 60 and it carries rigidly connected therewith by the pins 55 a thin plate 56 containing an aperture of 50 just sufficient size to allow the figures appearing upon the wheel 30 and fractional scale 50 to appear therethrough and indicate the desired reading. The plate 56 partakes, therefore, of any movement given to the segmental plate 52 but the aperture 55 57 in the base is made sufficiently large so that whatever position the segmental plate 52 may take the reading through the aperture in the plate 56 will always be visible.

The wheel 30 is provided on its periphery 60 with a series of holes 301 spaced to correspond with the numbers appearing on the face of the wheel and the segmental plate 52 carries a spring-pressed plunger 58 which locks the wheel and segmental plate 65 together by entering one of the said holes

301. It will thus be seen that by withdrawing the plunger 58 the carriage 13 is left free to be slid longitudinally until through its connection with the wheel, the desired figure on the wheel 30 appears through the aperture 56, when the plunger is allowed to spring in and lock the wheel 30 to the segmental plate 52. The fractional movement of the wheel 30 is secured by swinging the fractional scale plate 50 about its hub and thus through the metal band 53 moving the segmental plate 52 which is rigidly connected to the wheel 30 by the plunger 58 and the fractional amount moved is indicated by the figure on the fractional scale plate 50 appearing in the aperture 56. To secure this result with accuracy the hub 54 of the fractional scale plate 50 is provided with a projecting arm 59 upon which the adjusting and locking set screws 80 for the metal band 53 are mounted and which carries a spring-pressed plunger 591, adapted to enter one of a series of holes in the periphery of the segment block 592, fastened by set screws 593 to the radial 85 plate 60. The holes in the periphery of the segment block 592 correspond with the graduations on the scale plate 50, and in the construction illustrated represent tenth parts of the graduations on the wheel 30. 90

It will be observed that the longitudinal movement of the carriage 13 and the consequent movement of the wheel 11 in a path radially of the actuator 8 is obtained entirely from the rotation of the wheel 30. 100 The rotary adjustment of this wheel already described is insufficient to take care of all the factors required in the operation of this form of device, because it is necessary to provide for an unequal variation, and 105 for that purpose I provide the mechanism shown.

The brace member 320 is slotted radially from the axis 31 as indicated at 323, and a block 324 is mounted to slide in said slot and 110 carries rigidly connected therewith and extending vertically upward a post 70 entering a cam groove 71 in the lower face of the wheel 30. This cam groove extends in a course regularly and progressively distant from the axis 115 of the wheel 30. An auxiliary radial plate 80 slides at its forward end upon the bracket 34 and is pivoted between the said bracket and the stud 31 to the radial plate 60 by means of an annular flange 81 extending 120 into a corresponding annular groove in the plate 60. This auxiliary radial plate 80 has formed therein a radial slot 82 through which the post 70 passes, while the radial plate 60 is entirely cut away in the vicinity 125 of the post 70 so as not to contact therewith at any time. The plate 60 rests near its forward end upon the plate 80 and the two are secured together by a spring-pressed plunger 83 sliding in the plate 80 and entering one 130

of a series of holes 62 in the depending segmental flange 63 of the plate 60.

The plate 80 carries at its forward edge and secured thereto by set screws 84 a pointer plate 85. For a purpose to be described later, a scale plate 90 is mounted on top of the auxiliary radial plate 80 and carries on its face designations such as the numbers 2, 3, 4, etc., these numbers being arranged so that either may be brought into radial juxtaposition with the designations on the scale 61. This scale plate 90 at its inner end is bent downwardly and apertured to correspond with the hole 62 so that by withdrawing the plunger 83 sufficiently the scale plate 90 may be shifted to any desired position.

The foregoing description of the wheel 11 driven by the actuator 8, the carriage for 20 sliding the wheel radially of the indicator disks, and the mechanism for securing the desired radial adjustment of the carriage applies equally to the mechanism illustrated at the right hand side of Fig. 1, which mechanism is, save in the proportion of some of its parts, in all respects a duplicate of the mechanism described. In this second mechanism, shown at the right hand of Fig. 1, the wheel is indicated at 111, the carriage at 30 131, and the apertured plate through which the indicating figures appear at 560.

By arranging the apparatus with a plurality of wheels, such as 11 and 111, driven by the same actuator and by providing for an 35 independent radial adjustment of these wheels with respect to the single actuator, and by providing means for indicating and setting the radial position of each wheel independently of the other, it is possible upon 40 one setting of the superimposed indicators, or indicating disks, to make a plurality of separate calculations affecting the same subject; for example, in the case of the measurement of the area to be allowed for the 45 cutting of shoe parts for which this machine is particularly designed, one is enabled by the use of the machine illustrated to make the desired calculations with respect to two 50 separate parts or sets of parts of the same shoes. For further example, in shoes comprised of patent leather vamps and kid tops the area required to cut the vamps of patent leather and the area to cut the tops of kid for any desired number and assortment of 55 shoes can be calculated simultaneously by using one mechanism for each, and these mechanisms being adjustable separately enables the proper and different constants to be employed in each case.

60 The operation of the entire calculating apparatus disclosed in this application and the features of which are made the subject of this invention will be readily understood by anyone familiar with my aforesaid patent. 65 In the case of the present machine, as in the

case of that shown in the said patent, a table is first prepared showing the amount of leather which it is desired to allow for the cutting of the parts of one pair of shoes of a given size taking as a standard, such, for example, as in the present case, length 5, width D, which amount will be based upon, (1) an allowance for wastage, (2) the particular part or group of parts to be cut, (3) the particular style of the shoe, and (4) the kind of leather to be used. Such a table is based on the actual area of the shoe parts as determined by careful measurement and upon the particular manufacturer's experience and practice with reference to the allowances for wastage, and it may be in the following form:

	Kid.			Calf.		Patent leather.
	Tops.	Vamp, tip, fox.	Entire shoe.	Vamp, tip, fox.	Entire shoe.	
Cir. fox polish.....	142	117	251	115	242	101
Cir. fox button.....	153	118	167	114	256	98
Cir. fox blucher.....	141	116	249	116	240	99
fox polish.....	126	119	252	114	241	102
fox blucher.....	133	118	250	116	242	101
Low blucher.....	114	120	236	115	226	100
Str. fox blucher.....	123	124	249	121	239	111
Str. fox low blucher	109	123	236	119	219	109
Whole quar. polish.....	179	69	257	.....	246	65
Whole quar. button.....	188	68	271	.....	262	64

The foregoing table expresses in convenient form the ratio of the areas of the respective shoe parts. Substantially the actual area of the respective parts may be found in square feet and decimals thereof by dividing the values given above by 100.

The foregoing table applies only to shoes of the width D, adopted for convenience as a standard. To modify the amount required according to the change in width, the calculating apparatus is adjusted by withdrawing the plunger 83 and shifting the position of the radial plate 60 and the auxiliary radial plate 80 until the letter indicating the desired width appears in the pointer recess of the scale plate 90. The foregoing table also applies only to shoes of the length 5, adopted as a standard, and in order to modify the amounts in accordance with the lengths of the shoes, the indicators 2, 3, etc., are made use of as explained in my aforesaid patent. The number of 115 shoes is also taken care of by the extent to which these several indicators are rotated.

In some cases it is desirable to make a further modification by introducing another factor into the calculation. If, for 125 example, a job lot of leather is purchased by a manufacturer and it is desired to allow more leather for the cutting of shoe parts by reason of the inferior quality of the leather, or if an extra high grade of leather 130

is purchased, or leather having larger unbroken areas is purchased rendering possible the cutting of the same shoe parts from a less quantity, then the amount of leather required and indicated by this calculating apparatus may be modified in accordance with the conditions by use of the adjustable scale plate 90. As shown in the drawings, this scale plate is made with its pointer recess in line with the scale number 5, and when so set the operation of the machine will give results corresponding to the figures of the above table modified by (1) the widths of the shoes, (2) the lengths of the shoes, and (3) the number of the shoes in question. If now the plunger 83 be withdrawn and the scale plate 90 be shifted either to the right or to the left so as to bring a different number than 5 into the pointer recess of the plate 85 and then the said scale plate 90 be locked in this position by the return of the plunger 83, its pointer recess will have been shifted to the right or to the left and a new basis will have been established for determining the relative positions of the radial plate 60 and the auxiliary radial plate 80, because the letters on the scale 61 will now appear at the pointer recess in the scale plate 90 in a different radial position. By thus shifting the scale plate 90 the amount of leather required may be increased or diminished as desired.

The operation of the apparatus now needs little further explanation. Assume, for example, that it is desired to calculate the area required to cut a certain number of pairs of shoes having kid tops and patent leather vamps, tips, and foxings. The handle 22 is depressed, causing the wheel 11 to be freed from contact with the actuator 8, and the cam 25 operated to insure the appearance of the zero points in the cyclometer 23 and, if desired, the wheel may be locked in depressed position by the pin 29 entering the recess 290. If there is to be no special modification outside of the facts called for by the table the scale plate 90 is set with the number 5 showing in the pointer recess of plate 85. The plunger 83 is operated to lock the radial plate 60 and the auxiliary radial plate 80 together with the character "D" appearing in the pointer recess of the scale plate 90. The plunger 58 is then withdrawn and the carriage 13 slid along the ways 14 until the integral parts of the required number in the table appears at the opening in the plate 56, when the plunger is allowed to spring back into the hole in the periphery of the wheel 30. The plunger 591 is then withdrawn and the fractional scale plate 50 shifted until the required fractional part of the number appears in the aperture in the plate 56, when the plunger 591 is allowed to spring back into the proper hole in the segment block 592. The same procedure is fol-

lowed with respect to the other set of mechanism at the right hand side until the proper number for the other parts of the shoe appears at the aperture in the plate 560. If the width of the shoe to be calculated is to be other than D, the plunger 83 in each instance is operated and the radial positions of the radial plate 60 and the auxiliary radial plate 80 shifted to bring the required width at the pointer recess in the scale plate 90. The wheels 11 and 111 are then released by withdrawing the pins 29 and are allowed to come into contact with the actuator 8, and the indicator disks are then operated as in my aforesaid patent according to the number of the shoes and their respective lengths, and thereupon the desired areas will appear in the respective cyclometers.

It frequently happens in practice, owing to the size of lasts used, or for other reasons, that it is desirable to cut the shoe parts one half size in length, smaller or larger, than the actual calculated amount. I provide for this contingency by shifting the scale plate 90 to the left or right, which I find in practice to give substantially this desired variation. If the operator were called upon to allow for the half size in length in operating the indicators mistakes would be liable to occur, while by shifting the scale plate 90 the operator can operate the indicators according to the size required and the desired allowance will be made automatically by the machine. To enable this to be done the scale plate 90 is marked with legends "½ up," "½ down," and when these marks are placed opposite the apertures in the pointer plate 85 the desired result will be secured.

Having fully described my invention what I claim as new and desire to secure by Letters Patent is:

1. An apparatus for calculating areas of upper material for shoes, comprising a member movable an amount proportional to the number of shoes in question to determine one factor of the calculation, adjustable means for multiplying the factor so determined by a constant, a graduated member movable with said adjustable multiplying means to indicate its position, a plurality of different adjusting devices acting on said graduated member whereby the constant may be varied, and a registering device adapted to indicate the final result.

2. An apparatus for calculating areas of upper material for shoes, comprising a member movable an amount proportional to the number and length of the shoes in question to determine one factor of the calculation, adjustable means for multiplying the factor so determined by a constant, a graduated disk movable with said multiplying means to indicate its position, independent controlling devices acting on said disk to

- adjust its position, and a registering device adapted to indicate the final result.
3. A calculating apparatus comprising a plurality of independently operating registering devices, a common actuator therefor, a series of independently operative indicators adapted to determine the movements of the actuator according to unit measurements which are proportional respectively to the areas of the different parts subjected to calculation, means for changing the relation of each registering device independently of the other with respect to the actuator to multiply as required the result indicated by the registering device.
4. A calculating apparatus comprising a series of indicators graduated in multiples of units having a predetermined proportion to one another, an actuator operated by said indicators and having its movement equal to the cumulative movement of the indicators, a plurality of registering devices independently operated by said actuator, and means for changing the effective relation of each registering device independently of the other with respect to the actuator to multiply as required in securing the result indicated by the registering device.
5. A calculating apparatus comprising, in combination, a rotary plate constituting an actuator, a series of indicators adapted to govern successive movements of said plate in one direction, a plurality of independent wheels having peripheral contact with said plate, each wheel mounted to rotate on an axis extending radially with respect to the axis of said plate, a registering device for and operated by each wheel, and means for guiding the wheels for movement in divergent paths extending radially of the plate.
6. A calculating apparatus comprising, in combination, a rotary plate constituting an actuator, a series of indicators adapted to govern successive movements of said plate in one direction, a plurality of independent wheels having peripheral contact with said plate, each wheel mounted to rotate on an axis extending radially with respect to the axis of said plate, a registering device operated by each wheel, means for guiding the wheels for movement in divergent paths extending radially of the plate, and a graduated scale for each wheel to indicate the position of the wheel with relation to the axis of the plate.
7. A calculating apparatus comprising, in combination, an actuator, a series of indicators adapted to govern successive movements thereof in one direction, a registering device operated by said actuator, means for adjusting the relation of said registering device with respect to said actuator, a graduated scale to indicate the said relation, means for adjusting said scale, a supplementary scale on which the adjustments of the first mentioned scale are indicated, and means for adjusting the initial position of the supplementary scale.
8. A calculating apparatus comprising a revoluble actuating plate, a shaft, a friction wheel on said shaft, registering mechanism operated by said shaft, means for shifting said wheel radially of said actuating plate and for simultaneously depressing said wheel out of contact with said plate during its shifting movement.
9. A calculating apparatus comprising a revoluble actuating plate, a carriage mounted for rectilinear movement radially of said plate, a wheel mounted on said carriage, means for yieldingly holding the wheel in engagement with the plate arranged to permit it to be depressed out of contact therewith, and means for locking the wheel in a position remote from the plate.
10. A calculating apparatus comprising a revoluble actuating plate, a carriage mounted for rectilinear movement radially of said plate, a wheel mounted on said carriage, means for yieldingly holding the wheel in engagement with the plate and permitting it to be depressed out of contact therewith, a registering device connected to said wheel, and means for restoring said device to its zero position upon the depression of the wheel.
11. A calculating apparatus comprising a rotary actuator, a carriage mounted for rectilinear movement and radially of said actuator, a wheel mounted on said carriage and adapted to have peripheral contact with the actuator, a graduated wheel mounted on a pivot fixed with respect to said actuator, and a metal band connected at its ends to the carriage and extending about a segmental portion of said wheel whereby the rectilinear movement of the carriage and the rotary movement of the wheel occur synchronously and without lost motion.
12. A calculating apparatus comprising a rotary actuator, a carriage mounted for rectilinear movement and radially of said actuator, a wheel mounted on said carriage and adapted to have peripheral contact with the actuator, a graduated wheel mounted on a pivot fixed with respect to said actuator, a metal band connected at its ends to the carriage and extending about a segmental portion of said wheel whereby the rectilinear movement of the carriage and the rotary movement of the wheel occur synchronously and without lost motion, and means for moving the wheel independently of the carriage into and out of engagement with the actuator.
13. A calculating apparatus comprising a rotary actuator, a carriage mounted for rectilinear movement and radially of said actuator, a wheel mounted on said carriage

and adapted to have peripheral contact with the actuator, a graduated wheel mounted on a pivot fixed with respect to said actuator, a metal band connected at its ends to the carriage and extending about a segmental portion of said wheel whereby the rectilinear movement of the carriage and the rotary movement of the wheel occur synchronously and without lost motion, and means for yieldingly holding the wheel in engagement with the actuator and enabling it to be depressed out of contact therewith, the said movement of the wheel being independent of the carriage and thus independent of the metal band.

14. A calculating apparatus comprising a rotary actuator, a carriage mounted for rectilinear movement and radially of said actuator, a wheel mounted on said carriage and adapted to have peripheral contact with the actuator, a graduated wheel mounted on a pivot fixed with respect to said actuator, a metal band connected at its ends to the carriage and extending about a segmental portion of said wheel whereby the rectilinear movement of the carriage and the rotary movement of the wheel occur synchronously and without lost motion, and means for adjusting the angular position of the graduated wheel.

15. A calculating apparatus comprising a rotary actuator, a carriage mounted for rectilinear movement and radially of said actuator, a wheel mounted on said carriage and adapted to have peripheral contact with the actuator, a graduated wheel mounted on a pivot fixed with respect to said actuator, a metal band connected at its ends to the carriage and extending about a segmental portion of said wheel whereby the rectilinear movement of the carriage and the rotary movement of the wheel occur synchronously and without lost motion, and means for adjusting the angular position of the graduated wheel.

16. A calculating apparatus comprising a rotary actuator, a carriage mounted for rectilinear movement adjacent to said actuator, a wheel mounted on said carriage and adapted to have peripheral contact with the actuator, a graduated wheel mounted on a pivot fixed with respect to said actuator, a metal band connected at its ends to the carriage and extending about a segmental portion of said wheel whereby the rectilinear movement of the carriage and the rotary movement of the wheel occur synchronously and without lost motion, and a plurality of cumulatively acting means for adjusting the angular position of the graduated wheel.

17. A calculating apparatus comprising a revolute actuator, a wheel mounted to have

peripheral contact with said actuator and to move longitudinally and radially of said actuator, a graduated wheel provided with a cam groove in its face and mounted on a pivot fixed with respect to said actuator, means for imparting longitudinal movement to said wheel from the rotary movement of said graduated wheel, a radial plate mounted on the axis of the graduated wheel, an auxiliary radial plate having a radial slot therein and pivotally mounted on said first radial plate, a stud mounted to move on a fixed radius of said graduated wheel and extending up through said slot into said cam groove, and means for shifting the relative position of said radial plate and said auxiliary radial plate.

18. A calculating apparatus comprising a plate, a graduated wheel, means for locking said wheel against rotation with respect to said plate at points determined by the graduations on the wheel, a fractional scale plate pivotally mounted on said plate, connections between said fractional scale plate and said graduated wheel whereby upon the adjustment of the fractional scale plate about its pivot the graduated wheel is given a corresponding fractional movement with respect to said first named plate.

19. A calculating apparatus comprising a radial plate, a graduated wheel, a segmental plate mounted for movement on said radial plate, radially of the wheel, a device for locking the segmental plate to the wheel at points determined by the graduations thereon, a fractional scale plate pivotally mounted on the radial plate, connections between the fractional scale plate and the segmental plate whereby the fractional movement of the said fractional scale plate about its pivot effects a fractional movement of the graduated wheel.

20. A calculating apparatus comprising a radial plate, a graduated wheel, a segmental plate mounted for movement on said radial plate, radially of the wheel, a device for locking the segmental plate to the wheel at points determined by the graduations thereon, a fractional scale plate pivotally mounted on the radial plate, connections between the fractional scale plate and the segmental plate whereby the fractional movement of the said fractional scale plate about its pivot effects a fractional movement of the graduated wheel, and means for locking said fractional scale plate in any desired adjusted position.

21. A calculating apparatus comprising a graduated wheel having a cam groove in its face, a radial plate pivoted coaxially with said wheel, means for securing the rotary adjustment of said graduated wheel with respect to said radial plate, an auxiliary radial plate pivoted to said radial plate at a distance from the axis thereof

and provided with a radial slot, a post extending through said slot into said cam groove, and means for limiting the travel of said post along a fixed radius of said wheel.

22. A calculating apparatus comprising a graduated wheel having a cam groove in its face, a radial plate pivoted coaxially with said wheel, means for securing the rotary adjustment of said graduated wheel with respect to said radial plate, an auxiliary radial plate pivoted to said radial plate at a distance from the axis thereof and provided with a radial slot, a post extending through said slot into said cam groove, means for limiting the travel of said post along a fixed radius of said wheel, and means for locking the said radial plate and auxiliary radial plate together in any relative adjusted position.

23. A calculating apparatus comprising an actuator, a wheel moved by said actuator, a registering device connected to and operated by said wheel, means for depressing said wheel out of contact with said actuator and simultaneously restoring the registering device to its zero position.

24. A calculating apparatus comprising a shaft, a measuring wheel carried by and operating said shaft, a registering device connected to and operated by said shaft, a cam mounted on said shaft and presenting inclined surfaces symmetrically disposed with respect to the zero position of the registering device, a device for depressing said shaft provided with pins adapted to contact with the surfaces of said cam and automatically restore the registering device to zero position upon the depression of the shaft.

25. A calculating apparatus comprising a movable actuator, a carriage mounted for movement with respect to the actuator in a predetermined path, a registering device mounted in the carriage and arranged to be operated by the actuator, a graduated wheel for indicating the position of the carriage, and a metal band extending between the carriage and the wheel.

50 26. A calculating apparatus having, in combination, a movable actuator, a registering device arranged to be moved bodily into or out of operative relation with said actuator and a wedge-shaped cam connected to said registering device and arranged to insure its return automatically to zero setting when moved out of operative relation with the actuator.

60 27. A calculating apparatus having, in combination, a movable actuator, a registering device arranged to be brought into and out of operative relation with the actuator

by relative movement of the two, a lever for moving the two apart, and means actuated by the lever for positively bringing the register to a predetermined setting during the relative movement in one direction of the actuator and register.

28. A calculating apparatus having, in combination, a movable actuator, a plurality of length indicators controllably related thereto, a registering device arranged to be operated by the actuator, means for moving said register into different predetermined positions corresponding to different widths, independent means for moving said register into different predetermined positions corresponding to different grades of material to be cut, a scale indicating grades, and separate means for moving the grade scale into different predetermined positions to cause the reading of the register to be reduced or increased.

29. A calculating apparatus having, in combination, an actuator movable about a fixed axis, a registering device movable toward and from said axis, and a graduated disk 30 for indicating the position of the register and being mounted to turn on a fixed axis at one side of the axis of the actuator and connected with the actuator for movement simultaneously therewith.

30. A calculating apparatus including a movable carriage, a registering device mounted therein, a graduated wheel for indicating the position of the carriage, a metal band extending between the carriage and the wheel, and means for taking up the band to adjust preliminarily the position of the carriage with respect to the graduated wheel.

31. An apparatus for calculating upper material areas for shoes, comprising a rotatable actuator arranged to be moved through an angle dependent upon the number and size of the shoes in question, a plurality of separate registering devices each arranged to be advanced by the movement of the actuator amounts proportional to such movement and to indicate respectively the areas of the different materials of the uppers, means for adjusting each registering device in accordance with the different shoe widths, and means for individually adjusting each registering device in accordance with the different characteristics of the materials to be cut.

In testimony whereof, I have signed my name to this specification in the presence of two subscribing witnesses.

PAUL F. W. C. KRIPPENDORF.
